GIDEON PILLOW BROWN, OF LAKE FOREST, ILLINOIS, ASSIGNOR TO BLANCHE WRIGHT BROWN, OF LAKE BLUFF, ILLINOIS.

HAND-HOLE SCRAPER.

1,308,222.

Specification of Letters Patent.

Patented July 1, 1919.

Application filed February 9, 1914, Serial No. 817,454. Renewed November 8, 1918. Serial No. 261,716.

To all whom it may concern:

Be it known that I, GIDEON PILLOW BROWN, a citizen of the United States of America, and resident of Lake Forest, Lake county, Illinois, have invented a certain new and useful improvement in Hand-Hole Scrapers, of which the following is a specification.

My invention relates to scrapers in general, but more particularly to boiler hand hole scrapers of the kind disclosed in my prior application No. 798,423. In a scraper of this particular character, the blades are automatically moved toward and away from the axis of rotation, in order that they may follow the oval line of the hand hole.

Objects of my present invention are to provide blades having a more effective cutting formation than heretofore; to provide means for taking up wear, when the blades become worn, whereby the cutting edges of the blades will always properly engage the edges of the hand hole; to provide means for closing the space between the rotary head and the stationary support, which space is necessary for taking up the wear on the blades; to provide means whereby the stationary support will firmly engage different hand holes of approximately the same size and shape, but which may not always be exactly the same; to provide a more effective formation of the gripping fingers by which the structure as a whole is held in place and drawn outward to bring the blades into proper engagement with the edges of the hand hole; and to provide certain combinations and details of construction tending to increase the general efficiency and serviceability of a scraper of this particular character.

To the foregoing and other useful ends, my invention consists in matters hereinafter set forth and claimed.

In the accompanying drawings:

Figure 1 is a side elevation of a hand hole scraper embodying the principles of my invention, showing the adjacent portions of the boiler in section, and showing the device clamped in position to scrape the edges or marginal portions of the hand hole, the shank of the handle being shown broken away for convenience of illustration.

Fig. 2 is an inside end view of the scraper

and adjacent portions of the boiler shown in Fig. 1.

Fig. 3 is a reduced section on line 3—3 in Fig. 5.

Fig. 4 is a similar section on line 4—4 in Fig. 5.

Fig. 5 is a central longitudinal sectional view of the device shown in Fig. 1, on an enlarged scale.

Fig. 6 is a fragmentary view of the central portion of the scraper structure, showing the cap removed, and illustrating the manner in which the end of the shaft is connected by a cross pin with the head which carries the cutting blades.

Fig. 7 is a perspective of one of the scraping or cutting blades.

Fig. 8 is a detail fragmentary sectional view showing one of the spring devices by which the stationary support is held firmly in the hand hole, and which takes care of slight variations in the size and shape of the hand holes, thereby preventing looseness when the oval shaped supporting plate does not fit any particular hand hole.

As thus illustrated, my invention comprises a shaft A supported for rotation in an oval shaped plate B which latter is adapted to fit the oval hand hole in the boiler plate C, as shown more clearly in Figs. 1 and 2. This oval plate B is pro-

vided with an oval cam track b which is engaged by the rollers b¹ carried on the scraping or cutting blades D, which latter slide in radial guideways d formed on the inner surface of the rotary head E, which latter is secured in any suitable manner to the said shaft. For example, the shaft can be pro-

vided with a cross pin a adapted to engage notches a¹ formed in said rotary head, and the shaft can be held against endwise displacement in an outward direction by a cap e secured to said head, covering the end of the shaft. A round plate F bears against the inner surfaces of said blades, and is provided with radial slots f in which the rollers b¹ move back and forth when the shaft 100 is rotated. In order to take up wear, some space is left between the plate F and the stationary supporting plate B, a springy or resilient plate G is intersposed between the two plates, to occupy said space, this filler 105 plate having a flange g that closes the said

space at the outer edge of the plate F at all times. This is for the reason that the central portion of the filler plate G is bulged outwardly, whereby the outer edges of this 5 plate always bear against the plate B, so that the flange *g* always closes the space between the plates F and B, thereby preventing the scrapings from entering said space. As a matter of special improvement, each 10 blade has an outer angular flange or cutting portion *d*¹ which bears upon the oval surface surrounding the hand hole. It will be seen that these portions *d*¹ of the blades, which latter may be of any suitable number 15 (two being shown in the drawings), are disposed at such an angle that they produce a shearing cut on the surface of the edges of the hand hole, thus more effectively scraping and cutting away the hard substances which 20 invariably form on the seat of the hand hole—that is to say, on the oval surface which forms a seat for the hand hole plate. Also, as shown, the plate B is provided with radially disposed clamping fingers H which are 25 movable toward and away from the axis of rotation, being seated in radial guides formed in the said plate. These fingers, it will be seen, slide over the outer edge of the hand hole to hold the scraping blades 30 against the inner surface or seat of the hand hole, and for this purpose the fingers are preferably beveled at their outer ends, and their beveled surfaces are provided with grooves or channels *h*, the sharp ridges between these grooves or channels cutting into 35 the edge of the hand hole when the fingers are forcibly moved away from the shaft. For this adjustment of the fingers a rotary cam plate I is provided, having eccentric 40 grooves *i*, each groove engaging a pin *i*² on one of said fingers, it being observed that these fingers are four in number. This cam plate I is rotated by a crank handle *i*² connected thereto by a sleeve on the handle or 45 in any suitable manner. The collar J is loose on the shaft, it being observed that the only things which are fixed to the shaft are the rotary head E and the collar K, which latter is secured to the shaft in any 50 suitable manner. A spring L is interposed between the collars J and K, at the front of the tool head, and in this way said spring serves constantly to pull the rotary head toward the plate B. In other words, this 55 spring has a constant tendency to cause the blades D to move toward the fingers H, whereby said blades always bear hard against the oval seat around the hand hole, and wear on the edges of the blades is automatically taken up. If the boiler plate C 60 is thick, the spring L will be compressed to allow the blades D to move slightly away from the fingers H—that is to say, to permit the plate B to move outward sufficiently to 65 enable the fingers H to slide into engaging

position on the outer surface of the boiler plate. The plate M is secured in place upon the plate B to hold the fingers H and the cam plate I against displacement. The outer edge of the plate B is provided at intervals with springs N which engage the edges of the hand hole, and which are backed by spring pressed pins *n*, whereby these flexible portions N are pressed tightly against the edges of the hand hole. This, it will be 75 seen, enables the plate B to hold itself against lost motion in hand holes which are approximately the same in size and shape, but which are not exactly the same, and which vary to some extent. For example, if 80 the scraper is inserted in a hand hole which is of such a size and shape that the plate B does not tightly and accurately fit the edges of such hole, whereby, and without some provision to the contrary, the scraper would 85 wobble or shift sidewise during the scraping operation, the springs N take up the lost motion, and by engaging the edges of the hand hole prevent or greatly reduce the inclination of the scraper to shake or wobble 90 around in the hole.

From the foregoing it will be seen that I provide a scraper which can be used for cleaning the seat around the edge of an oval hand hole such as those with which 95 certain types of boiler are provided. The blades, by reason of their peculiar formation, very effectively cut away the substances which accumulate around the edges of these boiler hand holes. By reason of the 100 spring L and the variable space between the plates B and F, the blades always bear hard upon the surface to be cleaned, regardless of the extent to which the blades have been worn, and regardless of the variation in the 105 thickness of the boiler plate. Also, and by reason of the grooved or corrugated formation of the beveled surface of the outer ends of the fingers H, the scraper is more effectively held in position, and this effect is 110 augmented by the provision of the springs or engaging portions N, in the manner previously described. It will be understood, of course, that the blades can be made of 115 steel or other suitable material, and the balance of the structure can be made of iron or steel, although the plate G is preferably of brass. The shaft A can be rotated in any suitable manner, after the scraper is secured in the hand hole, as by a handle O secured 120 to the outer end of said shaft.

I do not limit myself to the exact construction shown and described.

What I claim as my invention is:—

1. A scraper comprising a stationary support, a shaft extending through said support, a rotary head on said shaft, one or more blades carried on said head, and a filler between said head and support, permitting movement of said head toward the 130

- support to take up wear on said blade or blades, disposed between the opposing surfaces thereof.
2. A scraper comprising a stationary support, a shaft extending through said support, a rotary head on said shaft, one or more blades carried on said head, and a filler between said head and support, permitting movement of said head toward the support to take up wear on said blade or blades, disposed between the opposing surfaces thereof, and a spring on said shaft, tending to draw the head toward said support.
3. A scraper comprising a stationary support, a shaft extending through said support, a rotary head on said shaft, one or more blades carried on said head, and a filler between said head and support, permitting movement of said head toward the support to take up wear on said blade or blades, disposed between the opposing surfaces thereof, and spring devices for the said support, disposed on the periphery thereof, providing engaging portions which are movable toward and away from said shaft.
4. A scraper comprising a stationary support, a shaft extending through said support, a rotary head on said shaft, one or more blades carried on said head, and a filler between said head and support, permitting movement of said head toward the support to take up wear on said blade or blades, disposed between the opposing surfaces thereof, and clamping fingers for said support, extending beyond the periphery thereof, movable toward and away from said shaft, each finger having a grooved engaging surface.
5. A scraper comprising a stationary support, a shaft extending through said support, a rotary head on said shaft, one or more blades carried on said head, and a filler between said head and support, permitting movement of said head toward the support to take up wear on said blade or blades, disposed between the opposing surfaces thereof, and a spring exerting its tension on said head and support to take up wear.
6. A scraper provided with a blade having a cutting flange disposed with its edge at an oblique angle to the direction of travel thereof, to produce a shearing cut on the surface to be cleaned, a head on which said blade is mounted and a shaft for rotating
- said head, said cutting edge being disposed at an oblique angle to a line radial to said shaft, and in a plane at right angles to the axis of rotation.
7. A scraper provided with a blade having a cutting flange disposed with its edge at an oblique angle to the direction of travel thereof, to produce a shearing cut on the surface to be cleaned, a head on which said blade is mounted and a shaft for rotating said head, said cutting edge being disposed at an oblique angle to a line radial to said shaft, and in a plane at right angles to the axis of rotation, said flange having its end formed with another cutting edge for cleaning a surface disposed at an angle to said other surface.
8. A scraper comprising a stationary support, a shaft extending through said support, a rotary head on said shaft, one or more blades carried on said head, and a filler between said head and support, permitting movement of said head toward the support to take up wear on said blade or blades, disposed between the opposing surfaces thereof, said filler comprising a resilient plate having a flange extending along the outer edge thereof.
9. A scraper comprising a stationary support, a shaft extending through said support, a rotary head on said shaft, one or more blades carried on said head, and a filler between said head and support, permitting movement of said head toward the support to take up wear on said blade or blades, disposed between the opposing surfaces thereof, said filler comprising a plate having a springy bulge at the center thereof, around said shaft, and provided with means for preventing the scrapings from entering between said surfaces.
10. A scraper comprising a rotary cutting head, a support therefor, means for providing a variable space between said head and support, and means for closing said space to prevent the admission of scrapings thereto, constructed and arranged to automatically adjust itself to variations of said space.

Signed by me at Chicago, Illinois, this 29th day of January, 1914.

GIDEON PILLOW BROWN.
